DESIGN FOR A COMBINED SHELF AND ROLL CURTAIN WALL PROTECTOR

Edward Prinz, St. Paul, Minn.

Application September 10, 1945, Serial No. 121,969

Term of patent 14 years

(Cl. D21—6)

To all whom it may concern:

Be it known that I, Edward Prinz, a citizen of the United States and residing at St. Paul, in the county of Ramsey and State of Minnesota, have invented a new, original, and ornamental Design for a Combined Shelf and Roll Curtain Wall Protector, of which the following is a specification, reference being had to the accompanying drawings, forming a part thereof.

I claim:

The ornamental design for a combined shelf and roll curtain wall protector, as shown.

EDWARD PRINZ.
